UNITED STATES PATENT OFFICE.

JESSE E. SMITH, OF WORCESTER, MASSACHUSETTS, ASSIGNOR TO OSGOOD BRADLEY COMPANY, OF WORCESTER, MASSACHUSETTS, A CORPORATION OF MASSACHUSETTS.

CAR-SEAT.

1,161,899.

Specification of Letters Patent. Patented Nov. 30, 1915.

Application filed April 30, 1915. Serial No. 25,035.

To all whom it may concern:

Be it known that I, JESSE E. SMITH, a citizen of the United States, residing at Worcester, in the county of Worcester and 5 State of Massachusetts, have invented a new and useful Car-Seat, of which the following is a specification.

This invention relates to a car seat and particularly to improved devices for supporting and actuating a movable foot rest 10 associated therewith.

In the construction and operation of reversible cross seats in passenger cars, it has been found desirable to provide a foot rest 15 at the back of each seat for the comfort and convenience of the passenger in the seat immediately to the rear thereof. When the seat is reversed, as by throwing over the back, it is then necessary to provide a foot 20 rest under the opposite edge of the seat. It was the former practice to accomplish this result by providing a fixed foot rest under each edge of the seat. This arrangement however interfered materially with the placing 25 of hand baggage beneath the seats and also with the effective cleaning of the cars. Various arrangements were therefore proposed for removing the forward foot rest from operative position. This result has 30 been found to be most conveniently and effectively attained by using a single foot rest pivoted to swing beneath the seat and by providing suitable connections from the foot rest to the movable back and seat cushion 35 whereby movement of the back and cushion to either position will result in simultaneous movement of the foot rest to a corresponding position.

It is the object of my invention to improve 40 the actuating mechanism for foot rests of the latter type, by which improvements the construction is simplified and the efficiency of operation is materially increased.

With this object in view my invention relates 45 to certain devices, arrangements and combinations of parts which will be herein-after described and more particularly pointed out in the appended claims.

A preferred form of the invention is 50 shown in the drawings, in which—

Figure 1 is a front elevation of a car seat embodying my improvements; Fig. 2 is a vertical sectional view taken along the line 55 2—2 in Fig. 1; Figs. 3 and 4 are views simi-

lar to Fig. 2 but showing the parts in different relative positions; Fig. 5 is a partial longitudinal sectional view taken along the line 5—5 in Fig. 3, and Fig. 6 is a partial sectional view similar to Fig. 4 but having 60 the foot rest and its supporting arms removed to show the operation of the rocker actuating mechanism.

Referring to Fig. 1 I have shown my improved mechanism as embodied in a car seat 65 having end frames 10 and 11 firmly secured together by cross bars 12 and 13. The back 14 is carried by supporting arms 15 and 16 each provided with a pair of outwardly extending cylindrical lugs 17 (Figs. 2 and 5), 70 each pair of lugs being slidable in a cam groove 18 formed in the inner face of one of the end frames 10 or 11. As the back is thrown over from one edge of the seat to the other, its path of travel and its angular 75 position is defined by the lugs 17 and the cam grooves 18.

At their extreme ends the grooves 18 may be provided with depressed portions 19 within which one of each pair of lugs 17 80 is received as the back reaches its limit of travel in either direction. The depressions 19 tend to secure the back against accidental displacement and they also serve to increase the inclination of the back when in its final 85 position.

The seat cushion 20 is supported upon a pair of rocker plates 21 (Figs. 1 and 2) each provided with oppositely inclined surfaces 22 and abutments 23 upon its lower edge 90. The inclined surfaces 22 are designed to rest upon the cross bars 12 and 13, the cross bars being slightly cut away if necessary to provide a bearing for the rocker-plates. The abutments 23 are adapted to engage the 95 outer faces of the cross bars 12 and 13 to limit the movement of the rocker-plates in either direction.

Actuating connections are provided between the back supporting arms 15 and 16 100 and the rocker-plates 21, by which the rocker-plates are moved simultaneously with the back but in a direction opposite thereto. These connections each comprise a lever 24 (Figs. 5 and 6) secured to a cross shaft 105 25 supported in bearings in the end frames 10 and 11. A stud 26 is mounted upon the inner side of the lower end of each back supporting arm 15 and 16 and projects through a slot 27 in the upwardly extending arm of 110

the lever 24. The lever 24 is also provided with a depending arm 28 having an inwardly projecting stud 29 positioned to engage the sides of a substantially vertical slot 30 formed in the lower portion of the corresponding rocker plate 21. At its upper end the slot 30 communicates with a cross slot 31 which performs no function but merely provides clearance for the cross shaft 25 as the rocker-plate is reciprocated. With these connections, movement of the back from one edge of the seat to the other will result in reverse movement of the rocker-plates, as will be clearly evident from Fig. 6 and from 15 a comparison of Figs. 2 and 4.

The foot rest 33 is mounted upon depending arms 34 loosely pivoted upon the cross shaft 25. At its upper end each of the arms 34 is enlarged to form a head 35 (Fig. 2) 20 having a flaring recess 36 in its upper central portion and having rounded under-cut projections 37 and 38 disposed symmetrically with reference to the shaft 25. Each rocker-plate 21 is cored out or recessed in 25 its central portion to receive the head 35 of one of the arms 34 and a stud 40 carried by each rocker-plate projects into the cored opening thereof and coöperates with the flaring recess 36 in the upper end of one of 30 the arms 34. The opposite ends of the cored opening in the rocker-plate are shaped to provide cam surfaces 41 and 42 (Fig. 2) positioned to coöperate with the rounded projections 37 and 38 of the heads 35. At 35 their upper extremities the cam surfaces 41 and 42 are continued to form depressions 43 and 44.

When the seat back is in its right hand position, as viewed in Fig. 2, the rounded projection 37 of each arm 34 rests within the corresponding depression 43 and the coöperation of the parts 37 and 43 locks the foot rest against movement toward its left hand position. In this position it will be also noted that the stud 40 is substantially out of operative relation with the recess 36. As the seat back is thrown over from the position indicated in Fig. 2 to that indicated in Fig. 4 the rocker-plates 21 are moved from left to right and by such movement swing the foot rest from right to left. The first effect of the movement of the rocker plates is to swing the foot rest slightly further to the right until the projections 37 pass out of 55 the depressions 43, the studs 40 at the same time entering the recesses 36 (Fig. 3). During further movement of the rocker-plates to the right, each stud 40 actuates its swinging arm 34, and each projection 37 moves 60 downward along the corresponding cam surface 41, the parts in their mid-position being shown in Fig. 3. During continued movement of the rocker plates to the right

the projections 38 engage the cam surfaces 42 and thereafter assist the studs 40 in 65 swinging the foot rest to the left, the projections 38 eventually passing into the depressions 44 and locking the foot rest in its left hand position (Fig. 4). The locking engagement of the projections 37 or 38 with 70 their corresponding depressions 43 or 44 absolutely prevents movement of the foot rest or back by the application of pressure to the foot rest.

Having thus described my invention and 75 the operation thereof, it will be evident that changes and modifications can be made therein by those skilled in the art without departing from the spirit and scope thereof as set forth in the claims and I do not wish 80 to be otherwise limited to the details herein disclosed, but

What I do claim is:

1. In a car seat, in combination; a supporting frame, a back movable on said frame, cushion-supporting rocker plates 85 slideable on said frame, actuating connections from said back to said plates, a foot rest supported by arms pivoted to swing about a fixed axis, and coöoperating devices 90 on said arms and said rocker plates effective to move said rest in a direction opposite to the movement of said plates, said devices comprising a stud and opposed cam surfaces on each rocker-plate, a recess centrally disposed on each arm in position to coöperate 95 with said stud, and a pair of symmetrically-disposed projections on each arm, each effective to coöperate with one of said cam surfaces to swing said foot-rest from one of 100 its operative positions to its opposite position.

2. In a car seat, in combination, a supporting frame, a back movable on said frame, cushion-supporting rocker plates 105 slideable on said frame, actuating connections from said back to said plates, a foot rest supported by arms pivoted to swing about a fixed axis, and coöoperating devices on said arms and said rocker plates effective to move said 110 rest in a direction opposite to the movement of said plates, said devices comprising a stud and opposed cam surfaces on each rocker-plate, said cam surfaces being each continued 115 to form a depression at its upper end, means on each foot rest arm positioned to coöperate with said stud, and undercut projections on each arm effective to coöperate with said cam surfaces to swing said foot rest and each effective to engage one of said depressions to lock said foot rest in operative position.

In testimony whereof I have hereto set my hand.

JESSE E. SMITH.
